Patented Aug. 14, 1917.

UNITED STATES PATENT OFFICE.

MANFORD HORN, OF APPLETON, MINNESOTA.

TAG.

1,236,436.

Specification of Letters Patent. Patented Aug. 14, 1917.

Application filed December 17, 1914, Serial No. 877,744. Renewed January 16, 1917. Serial No. 142,743.

To all whom it may concern:

Be it known that I, MANFORD HORN, a citizen of the United States, residing at Appleton, in the county of Swift and State 5 of Minnesota, have invented a new and useful Tag, of which the following is a specification.

The device forming the subject matter of this application is a tag adapted to be employed for labeling exhibits at an exposition.

The tag is so constructed that a guard is adapted to be folded upon the body of the tag, thereby to cover and shield the name and address of the exhibitor during the 15 progress of the exposition. The guard is formed integrally with a sealing strip which is attached to the forward face of the body to hold the guard in place. Formed integrally with the sealing strip is a claim 20 check which is folded downwardly and overlaps the sealing strip and the guard.

The present invention aims to provide a novel means whereby the claim check may be detached readily, independently of the 25 sealing strip and the guard, and to provide a construction whereby the guard may be detached independently of the sealing strip and the claim check, the claim check remaining connected with the body portion of the tag when the guard is removed, and the guard and the sealing strip remaining connected with the body of the tag when the claim check is removed.

It is within the scope of the disclosure to 35 improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the 45 invention herein disclosed can be made within the scope of what is claimed without departing from the spirit of the invention.

In the accompanying drawing:

Figure 1 shows the tag in plan, and at full 50 length;

Fig. 2 shows the tag as the same will appear when the guard has been folded upwardly and after the sealing strip has been attached to the body of the tag;

Fig. 3 is a plan showing the tag as the 55 same will appear after the claim check has been folded downwardly from the position shown in Fig. 2;

Fig. 4 is an elevation wherein the tag is viewed edgewise, the same being in the 60 folded up condition of Fig. 3;

Fig. 5 is a fragmental plan showing a slight modification of the invention.

In carrying out the present invention there is provided a tag denoted generally 65 by the numeral 1 and comprising a body 2 provided adjacent one end 3 with primary data 4 concerning the article to be exhibited. The body 2 is provided adjacent its other end 5 with secondary data 6 concerning the 70 exhibitor, the two sets 4—6 of data being separated to define a sealing strip 7. A flap 8 is hinged as shown at 9 to said other end 5 of the body 2 and is provided with two transverse lines 10—11 of perforations. The 75 perforations divide the flap 8 into a claim check 12 at the free end of the flap 8, a guard 14 at the hinged end of the flap 8, and a sealing strip 15 between the claim check 12 and the guard 14. The sealing strip 15 80 is coated upon its forward face with an adhesive 16; the guard 14 being folded inwardly as shown at 17 along the line 9 upon the body 2 to hide the secondary data 6. The adhesive 16 on the sealing strip 15 is engaged 85 as shown at 18 with the body 2 along the sealing strip 7, the claim check 12 being folded outwardly as at 19 along the line of perforations 10 upon the sealing strip 15, and the guard 14. The guard 14 is severable 90 along its hinged union 9 with the body 2 and along the other line 11 of the perforations independently of the sealing strip 15 and the claim check 12. The claim check 12 is severable along the first specified line 11 95 of the perforations independently of the sealing strip 15 and the guard 14.

Noting particularly the perforations 11 and 10, it will be observed that the claim check 12 may be torn off without detaching 100 the sealing strip 15 or the guard 14 from the body 2. Similarly, a cut may be made along the hinged union 9, whereupon the guard may be detached along the line of perforations 11, the sealing strip 15 and 105 the claim check 12 remaining on the body 1.

The guard 14 may be inscribed upon its rear face as shown at 20, with directions

relative to the use of the guard. As shown at 21, the forward face of the claim check 12 may carry suitable directions relative to the use of this element of the structure.

5 The entire tag preferably is fashioned from a suitable grade of cardboard and may be provided with a reinforced eye 22.

10 In Fig. 5 of the drawings a slight modification of the invention is shown. In Fig. 10 5 the body of the tag is shown at 23, the guard at 24, the sealing strip at 25, the adhesive at 26 and the claim check at 27. The perforations which define the sealing strip 25 are shown at 28. The line of perforations indicated at 29 may replace the fold 9 of Fig. 1. The perforations shown at 29 are the sole distinguishing characteristic of the device shown in Fig. 5.

15 As clearly indicated by the reference 20 character 100 certain markings on the body portion of the tag are duplicated on the claim check. These markings permit each exhibitor of articles to be distinguished readily for identification upon presentation 25 of the claim check after the latter has been severed. The markings indicated at 100 of course may be of any desired form.

20 The guard 14 is securely held in place, during the judging of the exhibit, so as to 30 hide the name and the address of the exhibitor at 6. After the prizes have been awarded, the guard may be detached as hereinbefore stated. The name and address 35 of the exhibitor, is, therefore, in the interest of fairness, hidden before an award is made, but is exposed to the public after the award has been made.

Having thus described the invention, what is claimed is:—

An exhibition tag comprising a body provided adjacent one end with primary data concerning the article to be exhibited, and provided adjacent its other end with secondary data concerning the exhibitor, the two sets of data being separated to define a sealing strip; there being a flap hinged to said other end of the body and provided with two transverse lines of perforations dividing the flap into a claim-check at the free end of the flap, a guard at the hinged end of the flap, and a sealing-strip between the claim-check and the guard, one sealing-strip being coated upon its forward face with an adhesive; the guard being folded inwardly upon the body to hide the secondary data, and to bring the sealing-strips together, the claim-check being folded outwardly upon the flap-carried sealing-strip and the guard along one line of the perforations, the guard being severable along its hinged union with the body and along the other line of perforations independently of the sealing-strip and the claim-check, and the claim-check being severable along the first specified line of perforations independently of the flap-carried sealing-strip and the guard.

In testimony that I claim the foregoing as my own, I have hereto affixed my signature in the presence of two witnesses.

MANFORD HORN.
